INLAID ARTICLE AND METHOD

James J. Larmour, East Orange, N. J., assignor to
 Plastic Inlays, Inc., Summit, N. J., a corporation
 of New Jersey

Application July 30, 1938, Serial No. 222,188

12 Claims. (Cl. 41—35)

The present invention relates to inlaying and more particularly to the inlaying of translucent materials, although certain features may be utilized in other types of materials. The term "translucent" is used in the specification and claims herein, in its broad sense, to include both translucent and transparent materials.

An improved inlaid article and an improved method of inlaying is illustrated in the application of Milford Guy Sypher, Serial No. 24,518, filed in the United States Patent Office on June 1, 1935. The present invention is an improvement upon the invention of said application, and is particularly useful in connection with translucent and transparent materials and with certain other materials where special results and properties are desired.

An object of the present invention is to provide an improved inlaid article and an improved method of inlaying.

Another object of the invention is to provide an inlaid article made of translucent material and an improved method of inlaying said material.

Another object of the invention is to provide an inlay securely held in position.

Another object of the invention is to provide an inlay, the visible surface of which is flat.

Another object of the invention is to provide an inexpensive inlay of precious or semi-precious metal, by minimizing the amount of metal used.

Another object of the invention is to secure a very thin strip or design of expensive metal securely in position and to hold it flat against the bottom of a flat recess.

Another object of the invention is to provide an inlay of improved appearance without interrupting or disfiguring the exposed surface of the article.

Another object of the invention is to eliminate protruding parts of an inlay and to prevent dislocation of the inlay.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming a part of the specification, wherein

Fig. 1 illustrates the invention shown for illustrative purposes applied to a clock dial;

Fig. 2 is an enlarged sectional view illustrating details of the application of the inlay;

5 Fig. 3 is an illustration of a preferred method of inlaying the support, the tools being shown in inverted position to avoid inversion of the material being inlaid;

Fig. 4 is a modification of the invention illustrating an inlay utilizing a single strip or piece of metal;

10 Fig. 5 illustrates an inlaid article, which may be made of various types of material, in which the inlay is made in an aperture or perforation in the material; and

Fig. 6 illustrates a method of inlaying the article shown in Fig. 5.

Referring again to the drawing and more particularly to Figs. 1, 2 and 3 thereof, there is 20 shown a clock dial 4 having the usual Roman numerals 6 on the face thereof, so that the hour hand and minute hand may indicate the time. By showing the present inlay embodied in a clock dial, it is not intended that the invention be limited

25 to any specific article, as it may be applied to inlaying generally, and to various articles too numerous to specify herein. For example, the invention might be shown applied to fountain pens, pencils, instrument panels for automobiles, 30 signs, cameras, vanity cases, scales, telephones, presentation boxes, closure caps, and various other types of articles, as well as to the clock dial shown herein.

Referring more particularly to Fig. 2, showing 35 a section through the Roman numeral 1 of the dial, the dial 4 is preferably made of a translucent material, such as pyroxylin, although various other materials may be utilized. The material is preferably thin and has a series of recesses 5 formed on the rear side thereof conforming in shape to the Roman numerals intended to be indicated thereon. In each of the recesses, there is provided a strip or other configuration of material 6 adapted to lie flat on the bottom

40 of the recess, to give a regular flat surface without indentations, wrinkles or undulations. Preferably, the metal 6 is sufficiently stiff to retain its shape. In order to give it this rigidity and at the same time to furnish a surface of precious or semi-precious metal, a thin piece of base metal is utilized with a coating 7 of precious or semi-precious metal. This gives sufficient rigidity to facilitate insertion of the strip which gives 45 the visible indication on the dial and at the same time minimizes the cost.

A second strip or piece of material 8 is force fitted into the recess 5 over the material piece 6 to hold the latter in position and to form a backing therefor. Preferably, the holding member 8 is curved as shown in dotted lines in Fig. 2 before application, and is flattened during application to increase the lateral dimension thereof and to force the side edges firmly into the sides of the recess 5. Where the dial 4 is made of a translucent plastic such as pyroxylin, the edges 9 embed themselves in the material and securely fix the member 6 in position against the flat bottom of the recess, the member 6 being supported at substantially all points. The metal member 6, even if relatively thin, will prevent the edges 10 of the member 8 from being embedded in the bottom of the recess by guiding them toward the sides of the recess. If the inlay is in a shrinkable material such as pyroxylin, the shrinkage locks the parts more firmly in position and does not impair the inlay in any way. While the member 8 may be flush with the under surface of the dial or protrude slightly below it, it is shown in the preferred embodiment well above the surface of the dial to prevent protrusions likely to cause dislocation of the inlay.

The front of the dial 4 is smooth and uninterrupted. The inlays in the recesses 5 show through the translucent material and are plainly visible. The appearance of the dial is greatly enhanced over one in which the numerals are affixed to or painted on the outer surface. The appearance can be further enhanced by providing a light on the interior of the clock but such a light is not necessary to bring out the form and beauty of the inlay. The depth of the recess may be increased or decreased to regulate the thickness of the material at the bottom of the recess and thereby increase or decrease the conspicuousness of the inlay from the front of the dial.

A preferred method of inlaying the parts is shown in Fig. 3. The thin member 6 is placed in the bottom of the recess and the curved holding member 8 placed over it. The front side of the member 4 is supported by a support 10, and a tool 11 is forced into the recess 5 to flatten the member 8 and embed the edges thereof in the sides of the recess. Preferably, sufficient pressure is applied to cause engagement of the member 8 with the entire surface of the member 6 to hold it firmly against the bottom of the recess. The support 10 and tool 11 are shown in inverted position so that the position of the dial is the same in all of the figures. The tools may be adapted to apply one inlay at a time or to apply several or all inlays simultaneously.

The inlay shown in Fig. 4 differs from that shown in Figs. 1 to 3, in that a single strip of material 6' is utilized. It may have a surface 7' of precious or semi-precious metal. Preferably, the member 6' is curved as shown in dotted lines in Fig. 4, so that it may be readily placed in the recess 5. Thereafter, it is flattened to embed the edges into the sides of the recess to form a forced fit. The member 6' must have substantial rigidity in order to produce the desired result. Hence, the modification is more useful with plated metals, whereas the preferred embodiment may also be used with thin precious metals which lack rigidity by reason of their thinness.

In Fig. 5 the invention is shown applied to a member having a recess in the form of an aperture through the material. The member 6'' is

secured in the aperture flush with the front surface of the dial or other article 4. The holding member 8'' is secured in the aperture directly under the member 6'' and forms a backing therefor. If desired, the member 6'' shown in Fig. 5 may be additionally secured in position against accidental dislodgement by utilizing an adhesive substance between its lower surface and the member 8'' to hold both members securely together. A support 10 and tool 11 similar to the tools shown in Fig. 3 may be utilized for securing the inlay in position as shown in Fig. 6. The support positioned as shown, assures the surface of the member 6'' being flush with the front surface of the article. The embodiment illustrated in Fig. 5 is not as secure and sturdy as the preferred embodiment, but it may be desired in case of opaque materials and in certain other instances.

It will be seen that the present invention provides an improved inlay and an improved method of inlaying. The exposed surface of the article is unbroken and the letters or legends appear to be embedded or molded into the material, greatly enhancing the appearance of the article to which the inlay is applied. The parts are held rigidly in position and the visible member is held firmly against the bottom of the recess to keep it flat. The parts are inexpensive and readily manufactured without expensive machinery. Hence, articles may be inlaid at a minimum cost.

As various changes may be made in the form, construction and arrangement of the parts herein without departing from the spirit and scope 35 of the invention and without sacrificing any of its advantages, it is to be understood that all matter herein is to be interpreted as illustrative and not in a limiting sense.

Having thus described my invention, I claim:

1. A translucent member having a recess therein, a decorating material in said recess and conforming to the shape thereof, and a metallic member having its edges embedded in the sides of said recess and extending over said decorating material to hold said decorating material in the recess.

2. As an article of manufacture, a member formed of translucent material, having a recess on the underside thereof, a thin material in said recess visible from the front of said translucent member, and a metal holding member having a portion with a dimension slightly larger than the corresponding part of said recess frictionally engaging and tending to dig into the sides of said recess and extending over said thin material to hold it in position.

3. As an article of manufacture, a member of translucent material having a recess on the underside thereof, a relatively thin piece of metal in said recess having a surface of precious or semi-precious metal facing the bottom of the recess, and a relatively thick piece of metal with the edges thereof embedded in the sides of said recess to hold said metal in position.

4. As an article of manufacture, a member having an aperture therethrough, a piece of decorating material conforming to the shape of said aperture and substantially flush with the front surface of said member, and a relatively stiff piece of material having the edges thereof embedded in the sides of said aperture below said decorating material to form a backing therefor locked against movement in any direction with respect to the aperture.

5. As an article of manufacture, a member of

translucent material having a recess on the underside thereof, a piece of material in said recess conforming substantially to the shape thereof to decorate or provide legends on said member, and a piece of metal having its edges embedded in the sides of said recess to hold said decorating material in position, said piece of metal being below the surface of the underside of said translucent member.

6. As an article of manufacture, a member of translucent material having a recess on the underside thereof, a flat piece of metal in said recess conforming substantially to the shape thereof to decorate or provide legends on said member, a piece of curved metal fitting into said recess and having a size greater than the size of the recess with the edges embedded into the sides of said recess to hold said first piece of metal in position.

7. A translucent dial for a watch or clock, having recesses on the inner side thereof corresponding to the numerals desired on the face thereof, a material in said recesses and metallic members having their edges embedded in the sides of said recesses and extending over said material to hold said material against the bottoms of the recesses whereby said material is visible through said translucent dial.

8. The method of forming legends or configurations on a translucent member, which method comprises forming a recess on the underside of the member, placing a member having a surface of decorative metal in said recess, placing an oversize holding member in said recess over said decorative member and forcing the edges of said holding member against and into engagement with the sides of the recess.

9. The method of forming legends or configurations on a translucent member, which method comprises forming a recess on the underside of the member, placing in said recess a flat

opaque metal member having a surface of semi-precious metal adapted to show through said translucent material, and securing a curved holding metal member in said recess over said opaque member by flattening said curved member to increase the lateral dimension thereof and to embed the edges thereof in the sides of said recess.

10. The method of forming legends or configurations on a member, which method comprises forming an opening in said member, placing a decorating member in said opening, and securing said decorating member in position in said opening by a holding member, and securing the edges of said holding member to the sides of the opening by increasing an effective lateral dimension of the holding member so that the edges thereof tend to dig into the sides of the opening.

11. The method of forming legends or configurations on a translucent member, which method comprises forming a recess on the underside of the member, placing in said recess a decorating member having a surface adapted to show through said translucent member and securing a curved holding metal member in said recess over said decorating member by flattening said curved member to increase the lateral dimension thereof and to embed the edges thereof in the sides of said recess.

12. As an article of manufacture, a member having a recess therein, a piece of decorating material in said recess conforming to the shape of said recess and a relatively stiff piece of material in said recess extending over said decorating material, the edges of said stiff material being expanded outwardly and embedded into the sides of said recess whereby said pieces of material are retained in position without requiring support externally of the recess.
